UNITED STATES PATENT OFFICE

HERBERT S. JANDUS AND EVERETT R. KEELOR, OF DETROIT, MICHIGAN, ASSIGNORS
TO GENERAL SPRING BUMPER CORPORATION, OF DETROIT, MICHIGAN, A CORPORA-
TION OF MICHIGAN

DESIGN FOR A CLAMP PLATE FOR VEHICLE BUMPER

Application filed June 10, 1929. Serial No. 31,628. Term of patent 14 years.

To all whom it may concern:

Be it known that we, HERBERT S. JANDUS and EVERETT R. KEELOR, citizens of the United States, residing at Detroit, in the county of Wayne and State of Michigan, have invented a new, original, and ornamental Design for Clamp Plate for Vehicle Bumper, of which the following is a specification, reference being had to the accompanying drawing, forming part hereof, wherein—

Fig. 1 represents a front view and Fig. 2 a side view of a clamp plate for vehicle bumpers exhibiting our new design.

We claim:

The ornamental design for a clamp plate for vehicle bumper, substantially as shown.

HERBERT S. JANDUS.
EVERETT R. KEELOR.
